CLAIM

The ornamental design for a surgical stapler, substantially as shown and described.

DESCRIPTION

FIG. 1 is a perspective view of a surgical stapler showing our new design;

FIG. 2 is a side elevational view thereof looking from the right side of FIG. 3;

FIG. 3 is a front elevational view thereof;

FIG. 4 is a rear elevational view thereof;

FIG. 5 is a side elevational view thereof looking from the left side of FIG. 3;

FIG. 6 is a top plan view thereof; and

FIG. 7 is a bottom plan view thereof.
